TREATMENT OF HYDROCARBONS

Pike H. Sullivan, New Rochelle, N. Y., assignor to
 Gasoline Products Company, Inc., Newark, N. J.,
 a corporation of Delaware

Application November 18, 1933, Serial No. 698,569

10 Claims. (Cl. 196—9)

This invention relates to the production of valuable low-boiling normally liquid hydrocarbon oils, such as motor fuels of high anti-knock value, from normally gaseous hydrocarbons, and an object of my invention is to effect the production in an improved and efficient manner of normally liquid hydrocarbons, and especially those boiling within a gasoline or motor-fuel range, from gaseous mixtures containing a plurality of gaseous paraffins having higher molecular weights than methane, for example, ethane, propane, butane and pentane.

My invention has for further objects such additional improvements in operative advantages and results as may hereinafter be found to obtain.

My invention contemplates fractionating or rectifying a gaseous mixture containing a plurality of gaseous paraffins to separate a plurality of gas fractions relatively rich in individual paraffins, such as ethane, propane, butane, and pentane, the subjection of these gas fractions to individual gas cracking operations under optimum conditions with respect to the individual paraffin 20 gases for the production of gaseous olefins, and the subsequent combining of the olefinic products resulting from the several gas-cracking stages for subjection to elevated temperature and pressure effective to promote polymerization of 25 olefins to normally liquid hydrocarbons.

As starting material for my process, I may employ any gaseous hydrocarbon mixture containing substantial amounts of gaseous paraffins of higher molecular weight than methane. For example, I may employ gases produced during the cracking of petroleum oils or coal gas, and some 30 natural gases.

In order to make it possible to treat several paraffinic gases such as ethane, propane, butane and pentane under optimum conditions, the gaseous mixture is first fractionated or rectified in order to separate and separately recover fractions relatively rich in the individual paraffin gases; that is to say, containing the individual paraffin gases 40 in relatively pure and isolated form. Theoretically, if ethane, propane, butane and pentane are all present in substantial amounts, these can be recovered in substantially pure form as so many individual gaseous fractions, and reasonable 45 thoroughness of separation is always to be desired. In practice, however, recovery of the desired paraffinic gases in substantially more concentrated form is advantageous in any event, and the extent to which the separation is carried may 50 be considerably varied without departing from

my invention. Nor is it always necessary to recover as many fractions as there are desired paraffins present. For example, I may recover a fraction consisting largely of ethane, a second fraction containing propane, and a third fraction containing butane and pentane. In any event the gas fractions are separately and individually subjected to gas pyrolysis under preselected conditions, as will be described more fully herein below.

In its broadest aspect, my invention is not concerned with the particular manner in which fractionation is effected, and this may be accomplished in any known suitable manner. In a preferred and more specific form, however, the 15 fractionation is accomplished by means of absorbent oil, the absorption and separation of the individual fractions being effected by treating the gaseous mixture in a plurality of counter-current stages with carefully limited flows of absorbent oil to obtain selective effects. The absorbed hydrocarbons are then freed from the absorbent oil in a corresponding plurality of 20 stripping stages, preferably by convective distillation.

I have found that, whereas in the prior art it was customary to treat the several paraffinic gases together for the production of olefins, the best results may be obtained by separately and individually treating the several paraffinic gases 30 such as ethane, propane, butane, and pentane, or at any rate, gases relatively concentrated in these hydrocarbons, respectively, under conditions varying with respect to each other as to temperature, reaction time or both.

Thus, the pyrolysis of ethane is preferably conducted at a temperature of from 800° to 900° C.; that of propane at from 750° to 850° C.; that of butane at 700° to 800° C.; and that of pentane at 650° to 750° C., the temperature falling with increasing molecular weight, whereas if these gases are treated together the average temperature which will be necessary to be maintained will be too low to secure the optimum results as regards the conversion of ethane, and too high to secure 45 the best results with respect to the conversion of pentane and butane.

According to my invention therefore the several gas fractions are separately and individually treated at atmospheric pressure or moderately 50 elevated pressures not exceeding 200 pounds per square inch, and at temperatures within the ranges indicated, for periods of time sufficient to effect substantial degrees of conversion to olefinic products, and the resulting olefinic gases 55

resulting from the several gas pyrolysis stages are then combined and subjected to pressures of the order of 1000 to 3000 pounds per square inch, or even higher, and temperatures of from 5 300° to 600° C., although these limits are not absolutely necessarily adhered to, in order to effect a polymerization of normally gaseous olefins to normally liquid materials.

If desired, the polymerization may be conducted 10 in the presence of hydrocarbon vapors from another source; for example, the products from the cracking or reforming of low boiling hydrocarbon materials such as gasoline or naphtha, may be introduced into the polymerization 15 stage in accordance with the invention set forth in my application Serial No. 661,868 filed March 21, 1933. Or, if desired, other gases and oils may be introduced into the polymerizing chamber or into the stream of gases being delivered thereto, 20 for the purpose of modifying the polymerizing reactions, or for the purpose of controlling the temperature conditions during the polymerization stage.

The products resulting from the polymerizing 25 operation are withdrawn and fractionated in conventional manner to recover therefrom normally liquid hydrocarbons, and a portion or all of the remaining gases may be returned to the initial fractionation stage wherein the several gaseous 30 paraffins are separated.

As a rule, the gaseous mixtures which are available for the practice of my invention will contain considerable amounts of hydrogen as well as methane. It has been found that methane 35 does not respond readily to gas pyrolysis for the production of olefins, and it is an advantage of my present invention that in the preliminary gas-fractionation stage, hydrogen and methane are largely separated from the higher paraffins, 40 thus avoiding the presence of large quantities of these materials in the gas pyrolysis stages and making possible the recirculation of the gaseous products remaining after the polymerizing stage in the manner set forth hereinabove.

45 In order that these and other aspects of my invention may be clearly set forth, I now describe, with reference to the accompanying drawings, a preferred manner in which my invention may be practiced and embodied, but without limiting my 50 invention to such illustrative example or examples as are given hereinbelow. In these drawings:

Fig. 1 is a more or less diagrammatic elevational view of a system for effecting conversion 55 of gaseous paraffins to normally liquid hydrocarbons in accordance with my present invention; and

Fig. 2 is a similar view of an alternative or more specific form of a portion of the system illustrated in the preceding figure.

Similar reference numerals designate similar parts in both of the views of the drawings.

Referring now to the drawings, and more particularly Fig. 1, gases, such as cracking-plant 65 gases, containing ethane and higher gaseous paraffins, are delivered through a conduit 1 by means of a pump 2, or where possible, under their own pressure, to a fractionating stage 3 of any suitable type and wherein the gases are fractionated 70 or rectified to effect the separation of a desired plurality of fractions constituting, insofar as is possible or desired, the individual gaseous paraffins higher than methane in relatively pure form. While in Fig. 1 I have shown four fractions consisting largely of ethane, propane, butane and

pentane, as being removed from the fractionating stage 3 through lines 4, 5, 6 and 7, respectively, it will be understood that in accordance with the general description of my invention given hereinabove, the number and character of the various 5 fractions may be varied in accordance with the character of the gases initially treated and the nature of the results desired.

Residual gases such as hydrogen and methane which it is not desired to include in the fractions 10 separated for pyrolysis and polymerization are shown as being withdrawn from the fractionation stage 3 through a conduit 8.

Assuming that four fractions consisting of ethane, propane, butane, and pentane, respectively, have been withdrawn from the fractionating stage 3 through lines 4, 5, 6 and 7, these are then delivered by means of pumps 9, 10, 11 and 12, if necessary, to a corresponding plurality of gas pyrolysis furnaces 14, 15, 16 and 17, respectively, where these gaseous fractions are separately and individually treated under optimum temperature conditions ranging from about 650° C. to about 900° C., and preferably under a pressure not exceeding 200 pounds per square inch. 25 In a preferred instance in which four fractions are separated as indicated hereinabove, the specific operating temperatures in the furnaces 14, 15, 16 and 17 may be about 850°, 800°, 750° and 700° C., respectively. 30

In addition to varying the temperatures obtaining in the furnaces 14 to 17 the reaction times may likewise be varied. This is especially true where the temperatures obtaining in the various gas pyrolysis furnaces approach each other 35 closely.

In general the times of contact employed in the gas-pyrolysis stage will be relatively short, for example, from one second or even less to three seconds or even as high as five seconds, and for 40 any given gas will tend to decrease with rising temperatures.

Where desired, as for example where the concentration of pentane in the gases being treated is rather low, the furnace 17 may be omitted 45 and the fractionation conducted in such manner as to include whatever pentane is present in the fraction consisting largely of butane, and which is delivered to the furnace 16. In this instance, the temperature maintained in the furnace 16 50 will preferably be from 700° to 750° C., for example about 725° C. Or, if desired, the pentane and butane fractions may be included with the propane fraction delivered to the furnace 15, in which event furnaces 16 and 17 may both be 55 omitted. The furnace 15 in this instance will be maintained at a temperature of from 725 to 800° C., for example, about 775° C. It will be understood, however, that when the various fractions are thus combined, the specific operating 60 temperatures will depend not only upon the preferred temperature ranges indicated hereinabove with respect to the individual paraffins but will also depend to a considerable extent upon the proportions of the individual paraffins present in 65 the fractions undergoing pyrolysis.

The olefinic gases resulting from the pyrolyses taking place in the furnaces 14 to 17 are then combined and passed through a manifold line 18, a branch line 19 having valves 20 and 21, 70 and a line 22 to a compressor 23, which delivers the gases under a pressure of 1000 to 3000 pounds per square inch or higher, to a reaction chamber 24.

It is ordinarily desirable to maintain the gases 75

undergoing polymerization in the reaction chamber 24 at a temperature of from 300° to 600° C., and while the chamber 24 may be cooled for this purpose, it is ordinarily preferred to cool the gases in some manner prior to their entry into the chamber 24. This may be accomplished in any one of several manners, for example, by closing the valve 20 and permitting the gases from the furnaces 14 to 17 to pass through a branch line 25, having valves 26 and 27, to a cooler 28. As will be pointed out more fully in connection with Fig. 2, the cooling taking place in the cooler 28 may be sufficient to bring the olefinic gases down to substantially atmospheric temperature, or merely to the temperature desired to maintain in the chamber 24.

As an alternative method of cooling the gases, hydrocarbon gas or oil from an extraneous source may be introduced by means of a compressor or pump 31 and a line 32 to the inlet side of the compressor 23 which delivers the gases into the polymerization chamber 24. Various inert or diluent gases as well as reactive hydrocarbon gases, and various oils or tars, may be introduced to the polymerizing chamber as thus indicated.

Naphtha or gasoline of sufficiently low anti-knock value to warrant further cracking or reforming of the same may be introduced through a conduit 33 and a pump 34 to a heating coil located within a furnace 35, wherein the naphtha is subjected to cracking or reforming at temperatures of the order of 800° to 1300° F. under pressures of from 150 to 1000 pounds per square inch or higher, and the vaporous products resulting from such cracking or reforming may then be delivered by means of a conduit 36 to the chamber 24, or to the inlet side of the compressor 23 for delivery to the chambers 24.

In the instance illustrated in Fig. 1 it is assumed that the naphtha-reforming operation takes place in the furnace 35 under a pressure at least equal to that obtaining in the polymerizing chamber 24 and where this is true, as shown in the drawings, the products from the furnace 35 may be delivered directly to the chamber 24. Where, however, the reforming operation is conducted under a lower pressure than that obtaining in the polymerizing chamber 24, the reformed products, with or without cooling, as desired, may be compressed to a pressure at least equal to that obtaining in the polymerizing chamber 24 before being delivered to the latter.

As has been stated hereinabove, the gases are maintained within the chamber 24 for a period of time sufficient to effect polymerization of normally gaseous materials to normally liquid materials to a substantial extent. The products are then withdrawn from the chamber 24 to a conduit 37, which may be provided with valve 38, and passed to an evaporator or low-pressure chamber 41 located in the lower portion of a fractionating tower 42 provided with the usual plates or trays 43 and cooling means 44.

Under reduction of pressure and cooling effected in the fractionator 42, liquid products heavier than the desired motor fuel products are condensed and are withdrawn through valved lines 45 and 46 for disposal in any desired manner, and the lower-boiling hydrocarbon vapors, together with unconverted gases, pass through a vapor line 47 to a cooler 48, where the normally liquid hydrocarbons useful as motor fuel are condensed. The cooled products are delivered from the cooler 48 through a line 49 to a gas separator 50, from which the motor-fuel condensate is

withdrawn through a conduit 51 having a valve 52. The residual gases may be withdrawn from the system through a line 53 having a valve 54, or a portion or all of these gases may be returned through a line 55 having valves 56 and 57 to the inlet side of the pump 2 or directly to the fractionating stage 3. These gases will consist largely of methane, together with some hydrogen and considerable quantities of paraffinic and olefinic gases, and may advantageously be recirculated in view of the removal of methane and hydrogen in the fractionating stage 3.

In the instance illustrated in Figure 2, the preliminary fractionation of the paraffinic gases is accomplished in a plurality of absorption stages located in series in the path of the gases and wherein the gases are scrubbed with a solvent or solvents introduced in regulated quantities to give selective effects as regards the several paraffin constituents.

Referring to the figure, the fractionator 3 in this instance comprises a plurality of absorber sections 61, 62 and 63, through which the gas travels in the reverse order and in which the gases are successively subjected to countercurrent contact with a plurality of flows of absorbent oil or oils introduced into the absorbing sections in regulated amounts.

In the present instance, the introduction of absorbent oil into the section 63 is regulated to effect an absorption of butane and pentane to as complete an extent as possible without effecting any considerable absorption of paraffinic constituents of lower molecular weight. The introduction of absorbent oil to the section 62 is regulated to effect a selective absorption of propane, and the introduction of oil to the section 61 to effect a selective absorption of ethane, while hydrogen and methane and other residual gases pass out of the fractionator 3 through the conduit 8. It will be understood that with reference to both this figure and the preceding figure, olefinic constituents present in the gas (such as ethylene, propylene and butylene) will normally be absorbed together with the paraffinic constituents more nearly related thereto, respectively.

The enriched absorbents pass out of the sections 61, 62 and 63 through lines 64, 65 and 66 to corresponding heat exchangers 67, 68 and 69, and thence through lines 70, 71 and 72 to stripping stills 73, 74 and 75, respectively. If desired, preheaters (not shown) may be inserted in the lines 70, 71 and 72 for the purpose of imparting additional heat to the enriched absorbents.

In the stripping stills 73, 74 and 75, which are supplied with steam from lines 76, the absorbents are stripped of their respective contents of paraffinic gases. The latter pass off in vapor form with the steam, and the stripped absorbents then pass through lines 78, 79 and 80, wherein are located pumps 81, 82 and 83, respectively, through heat exchangers 67, 68 and 69, lines 84, 85 and 86, coolers 87, 88 and 89 and lines 90, 91 and 92 to the absorbing sections 61, 62 and 63, respectively, thus completing their respective cycles.

The vapors liberated in the stripping stills 73, 74 and 75, which (in addition to steam) contain ethane, propane and a mixture of butane and pentane, respectively, pass through vapor lines 93, 94 and 95 to condensers 96, 97 and 98 and water separators 101, 102 and 103. The gas fractions then pass through lines 104, 105 and 106, 75

wherein are located pumps 107, 108 and 109, to the gas pyrolysis furnaces 14, 15 and 16.

In the present instance, as has been indicated hereinabove, the ethane fraction passing through the furnace 14 is brought to a temperature of 800° to 900° C. The propane fraction passing through the furnace 15 is brought to a temperature of from 750° to 850° C. while the mixture of butane and pentane passing through the furnace 16 is carried to a temperature of from 700° to 750° C., all of these fractions being maintained at the indicated temperatures for sufficient time to effect the desired conversion to olefins.

15 The olefinic gases from the furnaces 14, 15 and 16 are then combined in the manifold line 18 and pass to the cooler 28 where, in the present instance, they are cooled to substantially atmospheric temperature. The products then pass 20 to a separator 111, from which any normally liquid material may be removed through a valved line 112, while the olefinic gases pass through a conduit 113 having a pump 114 to a coil 115 located within a suitable furnace 116 and wherein 25 the gases are brought to a temperature of from 300-600° C. under a pressure in excess of 1000 pounds per square inch, to effect polymerization of gaseous olefins to normally liquid materials.

The products of polymerization leave the furnace 116 through a line 117 having a valve 118. If the time of contact retained in the heating coil 115 is not sufficient or if further reaction is desired for any other reason, these products may be delivered to a polymerizing chamber such as 30 the chamber 24 of Fig. 1. Otherwise, the products are delivered through line 117 to the usual fractionation and condensing apparatus such as the fractionator 42 and condenser 48 of the preceding figure, for cooling and condensation of 35 normally liquid materials. As in the previous instance, after cooling to atmospheric temperature and separation of the desired liquid products, all or a portion of the gases may be returned to some earlier point in the system, for 40 example to the fractionating tower 3.

45 It will be understood by those skilled in the art that the various features of operation described in connection with the two figures are not necessarily limited to the specific examples in connection with which they have been described. For 50 example, condensation to atmospheric temperatures in the cooler 28 and the use of a coil furnace such as the furnace 116 may be employed in conjunction with the apparatus illustrated in 55 Fig. 1, and various other features of the two illustrative examples may be combined as desired.

While, in the illustrative examples given hereinabove, I have described several gas pyrolysis operations as being effected in furnaces of the fired-coil type, it will be obvious to those skilled in the art, in view of the low pressures maintained during the pyrolysis operations, that various other types of furnaces may be employed 60 for the purpose of effecting the pyrolysis of paraffins to olefins. For example, the several gas fractions separated in the preliminary fractionating stage may be subjected to pyrolytic operations conducted in refractory apparatus of relatively large internal capacity and heated intermittently and internally rather than continuously and externally. Such apparatus may be employed, for example, as that commonly used for the production of oil gas and carburetted 65 water gas.

As a further extension of my invention, the gaseous fraction removed from the fractionating stage 3, which comprises residual constituents such as methane and hydrogen, if sufficiently high in methane content may be subjected to 5 more drastic temperature conditions, for example, 1200° C. or higher, for the purpose of reforming the same, that is to say, for the purpose of effecting the breaking down of methane to hydrogen and carbon. The thereby re-formed 10 gas may then be employed for use as a fuel gas or for any other purpose, for example, as a source of hydrogen.

With further reference to the specific example illustrated in Fig. 2, it will be obvious to those skilled in the art that the absorbent oil or oils employed in the sections 61, 62 and 63 may comprise any of the hydrocarbon oils commonly employed for absorption purposes. Such oils should possess sufficient fluidity to enable easy handling 20 and boiling-point ranges sufficiently high to prevent substantial volatilization in the stripping stills. As an example of such an oil, gas oil boiling between 450° F. and 600° F. may be cited. While I have indicated that the oil employed in 25 sections 61, 62 and 63 may be different in character, ordinarily this is unnecessary as it is possible to obtain sufficiently selective results for most purposes by using the same oil in carefully regulated amounts, so that in each section only the 30 higher paraffin or paraffins are absorbed to the exclusion insofar as possible of lower paraffins.

While I have described my invention hereinabove with respect to several illustrative examples, it will be understood by those skilled in the 35 art that my invention is not limited to the details of these examples except as specifically set forth in the claims hereinafter made.

I claim:

1. The process of obtaining valuable liquid 40 hydrocarbons, which comprises intimately contacting a hydrocarbon mixture containing gaseous paraffins with liquid absorbent to separately and selectively absorb individual gaseous paraffins having more than one carbon atom in relatively pure states, recovering said gaseous paraffins from the absorbent, separately and individually subjecting said gaseous paraffins to pyrolysis under conditions of temperature and pressure adapted to produce optimum quantities of olefins 45 together with normally liquid hydrocarbons therefrom, separating normally liquid hydrocarbons thus produced from said olefinic gases, separately cracking low-boiling hydrocarbon oil, combining the olefinic gases resulting from said pyrolyses 50 and the products resulting from said cracking, subjecting the combined gaseous and vaporous products to conditions of high pressure and elevated temperature effective to promote polymerization of olefins to higher boiling products, and 55 fractionating the resultant products to recover normally liquid hydrocarbons therefrom.

2. The process of obtaining valuable liquid 60 hydrocarbons from a hydrocarbon mixture containing gaseous paraffins, which comprises intimately contacting said mixture with liquid absorbent to separately and selectively absorb individual gaseous paraffins having more than one carbon atom in relatively pure states, recovering said gaseous paraffins from the absorbent, separately and individually subjecting said gaseous paraffins to pyrolysis under conditions of temperature and pressure adapted to produce optimum quantities of olefins together with normally liquid hydrocarbons therefrom, combining ole- 65

- finic gases and normally liquid hydrocarbons resulting from said pyrolyses, separating said normally liquid hydrocarbons from said olefinic gases, subjecting other hydrocarbon fluid to a conversion operation, admixing products of conversion therefrom with said separated olefinic gases, subjecting the olefinic gases and admixed hydrocarbon fluid to conditions of high pressure and elevated temperature effective to promote polymerization of olefins to higher boiling products, and fractionating the resultant products to recover normally liquid hydrocarbons therefrom. 5
3. The process of obtaining valuable liquid hydrocarbons from a hydrocarbon mixture containing gaseous paraffins, which comprises intimately contacting said mixture with liquid absorbent to separately and selectively absorb individual gaseous paraffins having more than one carbon atom in relatively pure states, recovering 10 20 25 30 35 40 45 50 55 60 65 70 75
- said gaseous paraffins from the absorbent, separately and individually subjecting said gaseous paraffins to pyrolysis under conditions of temperature and pressure adapted to produce optimum quantities of olefins together with normally liquid hydrocarbons therefrom, combining olefinic gases and normally liquid hydrocarbons resulting from said pyrolyses, separating said normally liquid hydrocarbons from said olefinic gases, subjecting other hydrocarbon fluid to a conversion operation, admixing products of conversion therefrom with said separated olefinic gases, subjecting the olefinic gases and admixed hydrocarbon fluid to conditions of high pressure and elevated temperature effective to promote polymerization of olefins to higher boiling products, fractionating the resultant products to recover normally liquid hydrocarbons therefrom, and returning the remaining gases to said contacting stage. 4. The process of obtaining valuable liquid hydrocarbons from a hydrocarbon mixture containing gaseous paraffins, which comprises intimately contacting said mixture with liquid absorbent to separately and selectively absorb ethane and propane in substantially pure states, recovering said ethane and propane from the absorbent, separately and individually subjecting said ethane and propane to pyrolysis under conditions of temperature and pressure adapted to produce optimum quantities of olefins together with normally liquid hydrocarbons therefrom, combining olefinic gases and normally liquid hydrocarbons resulting from said pyrolyses, separating said normally liquid hydrocarbons from said olefinic gases, subjecting other hydrocarbon fluid to a conversion operation, admixing products of conversion therefrom with said separated olefinic gases, subjecting the olefinic gases and admixed hydrocarbon fluid to conditions of high pressure and elevated temperature effective to promote polymerization of olefins to higher boiling products, and fractionating the resultant products to recover normally liquid hydrocarbons therefrom. 5. The process of obtaining valuable liquid hydrocarbons from a hydrocarbon mixture containing gaseous paraffins, which comprises intimately contacting said mixture with liquid absorbent to separately and selectively absorb ethane, propane and butane in substantially pure states, recovering said ethane, propane and butane from the absorbent, separately and individually subjecting said ethane, propane and butane to pyrolysis under conditions of temperature and pressure adapted to produce optimum quantities of olefins together with normally liquid hydrocarbons therefrom, combining olefinic gases and normally liquid hydrocarbons resulting from said pyrolyses, separating said normally liquid hydrocarbons from said olefinic gases, subjecting other hydrocarbon fluid to a conversion operation, admixing products of conversion therefrom with said separated olefinic gases, subjecting the olefinic gases and admixed hydrocarbon fluid to a temperature of from 300 to 600° C. under a pressure of at least 1000 pounds per square inch to effect polymerization of olefins to higher boiling products, and fractionating the resultant products to recover normally liquid hydrocarbons therefrom. 6. The process of obtaining valuable liquid hydrocarbons from a hydrocarbon mixture containing ethane and propane, which comprises intimately contacting said mixture with liquid absorbent to separately and selectively absorb ethane and propane in relatively pure states, recovering said ethane and propane from the absorbent, separately subjecting said ethane and propane to a temperature of from 800 to 900° C. and a temperature of from 750 to 850° C., respectively, under pressures of not more than 200 pounds per square inch to produce olefins and normally liquid hydrocarbons therefrom, combining olefinic gases and normally liquid hydrocarbons resulting therefrom, separating said normally liquid hydrocarbons from said olefinic gases, subjecting other hydrocarbon fluid to a conversion operation, admixing products of conversion therefrom with said separated olefinic gases, subjecting the olefinic gases and admixed hydrocarbon fluid to a temperature of from 300 to 600° C. under a pressure of at least 1000 pounds per square inch to effect polymerization of olefins to higher boiling products, and fractionating the resultant products to recover normally liquid hydrocarbons therefrom. 7. The process of obtaining valuable liquid hydrocarbons from a hydrocarbon mixture containing ethane, propane and butane which comprises intimately contacting said mixture with liquid absorbent to separately and selectively absorb ethane, propane and butane in relatively pure states, recovering said ethane, propane and butane from the absorbent, separately subjecting said ethane, said propane and said butane to a temperature of from 800 to 900° C., a temperature of from 750 to 850° C. and a temperature of from 700 to 800° C., respectively, under pressures of not more than 200 pounds per square inch to produce olefins and normally liquid hydrocarbons therefrom, combining the olefinic gases and normally liquid hydrocarbons resulting therefrom, separating said normally liquid hydrocarbons from said olefinic gases, subjecting other hydrocarbon fluid to a conversion operation, admixing products of conversion therefrom with said separated olefinic gases, and subjecting the olefinic gases and admixed hydrocarbon fluid to a temperature of from 300 to 600° C. under a pressure of at least 1000 pounds per square inch to effect polymerization of olefins to higher boiling products, and fractionating the resultant products to recover normally liquid hydrocarbons therefrom. 8. The process of obtaining valuable liquid hydrocarbons from a hydrocarbon mixture containing gaseous paraffins, which comprises fractionating said mixture to separate individual gaseous paraffins having more than one carbon atom in relatively pure states, separately and individually subjecting said gaseous paraffins to conditions of temperature and pressure adapted to produce optimum quantities of olefins together with normally liquid hydrocarbons therefrom, combining olefinic gases and normally liquid hydrocarbons resulting from said pyrolyses, separating said normally liquid hydrocarbons from said olefinic gases, subjecting other hydrocarbon fluid to a conversion operation, admixing products of conversion therefrom with said separated olefinic gases, subjecting the olefinic gases and admixed hydrocarbon fluid to a temperature of from 300 to 600° C. under a pressure of at least 1000 pounds per square inch to effect polymerization of olefins to higher boiling products, and fractionating the resultant products to recover normally liquid hydrocarbons therefrom.

5 combining olefinic gases and normally liquid hydrocarbons resulting therefrom, separating said normally liquid hydrocarbons from said olefinic gases, subjecting other hydrocarbon fluid to a conversion operation, admixing products of conversion therefrom with said separated olefinic gases, subjecting the olefinic gases and admixed hydrocarbon fluid to conditions of high pressure and elevated temperature to effect polymerization of olefins to higher boiling products, and fractionating the resultant products to recover normally liquid hydrocarbons therefrom.

10 9. The process of obtaining valuable liquid hydrocarbons from a hydrocarbon mixture containing gaseous paraffins, which comprises fractionating said mixture to separate individual gaseous paraffins having more than one carbon atom in relatively pure states, separately and individually subjecting said gaseous paraffins to conditions of temperature and pressure adapted 15 to produce optimum quantities of olefins together with normally liquid hydrocarbons therefrom, combining olefinic gases and normally liquid hydrocarbons resulting therefrom, separating said normally liquid hydrocarbons from said olefinic gases, subjecting the olefinic gases to conditions of high pressure and elevated temperature in the presence of naphtha added to 20 said gases and extraneously heated to an ele-

25 vated conversion temperature and undergoing conversion to effect polymerization of olefins to higher boiling products, and fractionating the resultant products to recover normally liquid hydrocarbons therefrom.

5 10. The process of obtaining valuable liquid hydrocarbons from a hydrocarbon mixture containing gaseous paraffins, which comprises fractionating said mixture to separate individual gaseous paraffins having more than one carbon atom in relatively pure states, separately and individually subjecting said gaseous paraffins to 10 conditions of temperature and pressure adapted to produce optimum quantities of olefins together with normally liquid hydrocarbons therefrom, combining olefinic gases and normally liquid hydrocarbons resulting therefrom, separating said normally liquid hydrocarbons from said olefinic gases, subjecting the olefinic gases to 15 conditions of high pressure and elevated temperature to effect polymerization of olefins to higher boiling products, separately heating naphtha to a temperature sufficient to effect reformation thereof, combining naphtha thus heated with olefinic gases undergoing polymerization, and fractionating the resultant products to 20 recover normally liquid hydrocarbons therefrom.

25 PIKE H. SULLIVAN.
